COOLER FOR MILK OR OTHER LIQUIDS

Peter Ulrik Fredrik Blomquist, Gothenburg,
SwedenApplication December 8, 1936, Serial No. 114,839
In Sweden October 16, 1935

2 Claims. (Cl. 62—147)

This invention relates to a cooler for milk comprising a container adapted to contain a cooling medium and disposed within a milk-can in such a manner that it is accessible from the exterior of the milk-can and may be filled with cooling medium such as ice, a cooling mixture or the like and emptied of its contents without the milk-can being opened or the contents of the milk-can being disturbed.

10 One object of the invention is to provide a cooler of this type, which will be simple, cheap to manufacture and very efficient and durable in use.

With this and other objects in view there is 15 illustrated in the accompanying drawing one form, in which the invention may be conveniently embodied in practice.

The drawing shows a vertical sectional view 20 through an ordinary milk-can provided with a cooler according to the invention.

In the embodiment of the invention illustrated in the drawing the milk-can 1 is provided with a tubular container 2 for ice 3, cooling mixture or the like. In this embodiment the container is 25 fitted in the milk-can in such a manner that it may easily be removed, and the container is so designed that it may be filled or emptied without removement from the milk-can. The upper end of the container 2 is provided with a tubular flange 4 and projects at substantially right angle through the breast plate 5 of the milk-can. The flange 4 is fitted in a collar 6 welded to the breast plate 5, as indicated at 7. A cap 8, which may be provided with an air hole 9, is screwed onto 30 the collar 6. If desired a packing may be provided between the cap 8 and the end surface of the collar 6. The lower portion 10 of the container 2 is directed substantially at right angle to the bottom plate 11 of the milk-can and projects through said plate. The portion 10 has a flange 12 of the same outer diameter as the flange 14 at the upper end of the container, so 35 that the container can be removed and inserted through the collar 6. The projecting end of the portion 10 has a collar 13 screwed thereon, which collar forces the flange 12 against the bottom plate 11, so that a perfect seal is obtained. In the outer end of the collar 13 a plug 14 is screwed. Said plug is provided with a small drain hole 15 covered by a spring-actuated ball valve 16. The spring 17 of the ball valve is interposed between the ball and a perforated washer 18 disposed 40 between the plug 14 and the end surface of the

portion 10. It is thus possible to remove melting water or other liquid from the container without removing the plug 14.

The above described construction permits a very cheap manufacture of milk-cans adapted for the transportation and cooling of milk and a good seal of the milk-can as well as the container for the cooling medium is obtained, since the container is of simple and easily manufactured shape and the joints between the container and the milk-can are simple in construction and easy to make tight.

The details of the invention may naturally be subjected to modifications within the scope of the following claims. The container for the cooling medium may be connected to the milk-can by means of flanges welded, soldered or riveted to the milk-can and welded, soldered or pressed onto the container. The container for the cooling medium may also project through the bottom of the milk-can a sufficient distance to form a flange on the outside of the can, which flange may be welded or soldered to the can. The fastening and closing means for the container may naturally be modified in any suitable way. The container may also be connected to the bottom of the milk-can by means of suitable closing plugs. The volume and cooling surface of the container may be increased by forming the container to one or more loops, preferably disposed coaxially with the milk-can, so that no pockets 20 are formed in the container.

What I claim is:—

1. A milk-can provided with cooling means comprising a container disposed within said milk-can and adapted to contain a cooling medium, a downwardly inclined breast plate in said milk-can, an intake portion to said container disposed in said breast plate, and an outlet portion of said container disposed at substantially right angle to the bottom of the milk-can.

2. A milk-can provided with cooling means comprising a container disposed within said milk-can and adapted to contain a cooling medium, a downwardly inclined breast plate in said milk-can, an intake portion to said container disposed in said breast plate, an outlet portion of said container disposed at substantially right angle to the bottom of the milk-can, a closing plug provided in said outlet portion, and a valve such as a spring-actuated ball valve in said closing plug.

PETER ULRIK FREDRIK BLOMQUIST.
